UNITED STATES PATENT OFFICE

MATHIAS A. REITER, OF CHICAGO, ILLINOIS, ASSIGNOR TO GEIB & SCHAEFER CO., OF CHICAGO, ILLINOIS, A CORPORATION OF ILLINOIS

DESIGN FOR A CASE FOR MUSICAL INSTRUMENTS, SUCH AS AN ACCORDION OR THE LIKE

Application filed November 6, 1931. Serial No. 41,639. Term of patent 14 years.

To all whom it may concern:

Be it known that I, MATHIAS A. REITER, a citizen of the United States, residing at Chicago, in the county of Cook and State of Illinois, have invented a new, original, and ornamental Design for Cases for Musical Instruments Such as Accordions or the Like, of which the following is a specification, reference being had to the accompanying drawings, forming a part thereof.

In the drawings: Figs. 1 and 2 are perspectives, viewed from opposite sides, of a musical instrument case embodying the invention. Fig. 3 is a section of the case in closed position.

I claim:

The ornamental design for a case for musical instruments, such as an accordion or the like, as shown.

MATHIAS A. REITER.
